(57) **CLAIM**

The ornamental design for a “film sheet for use in antiballistic articles,” as shown and described.

DESCRIPTION

FIGS. 1 and 2 are top and bottom plan views, respectively, of a film sheet for use in antiballistic articles which embodies our new and original design therefore, the side views thereof being unornamented; and, FIGS. 3 and 4 are top and bottom perspective views, respectively, of the design depicted in FIGS. 1 and 2. The broken lines in the drawing represent the bounds of the claimed design and form no part of the claimed design.
